UNITED STATES PATENT OFFICE

FRANK J. BRIDGEMAN, OF CLEVELAND, OHIO, ASSIGNOR TO THE LAKE ERIE CHEMICAL COMPANY, OF CLEVELAND, OHIO, A CORPORATION OF OHIO

FOOT CONTROL CONTACT

Application filed April 23, 1931. Serial No. 532,327.

This invention relates to foot control contacts for the closing of electric circuits, and includes that kind of contact which may be operated by a movement of the foot, and that may be placed upon the floor beneath a desk or table, for example, under a bank teller's counter, store counter, desk, etc., and it also provides a shield or cover to protect the device from mechanical injury, dust, dirt, etc., and which shield may also be used as a foot rest.

The invention described herein is a modification of that described in my co-pending application, filed October 22, 1930, Serial Number 490,531.

One object of the invention is to provide a foot control contact for use in electric protection systems used in banks, stores, etc., that is actuated by a movement of the foot and thereby close an electric circuit which latter includes a source of electricity, and the electric devices which are intended to discharge asphyxiating or other disabling or irritating gases for the purpose of disabling bandits or other criminals who are attempting robbery or other unlawful acts, and thereby enabling their capture.

A further object is to provide a foot operated contact means in which the contact actuating means is normally locked against movement, and requires an unlocking movement before the electric contacts can be closed.

Other objects of the invention will be apparent to those skilled in the art upon reading the specification.

In the accompanying drawings,

Fig. 1 is a view in perspective of one type of a completed foot control contact;

Fig. 2 is a vertical sectional view on the line 2, 2, of Fig. 5, looking to the right;

Fig. 3 is a vertical sectional view on the line 3, 3, of Fig. 5, looking to the right;

Fig. 4 is a vertical sectional view of the contact, on the line 4, 4, of Fig. 6, looking

towards the right, showing a foot in elevation, and with the movable elements raised;

Fig. 5 is a horizontal view, partly in section, looking down from the top on the line 5, 5, of Fig. 2, showing the electric contacts open, and also showing certain parts in elevation; and

Fig. 6 is a horizontal longitudinal view partly in section and partly in elevation looking down from the top on the line 6, 6, of Fig. 4, and showing one electric contact, at the left, closed.

The foot control contact as illustrated, consists of a rigid structure having a pair of upright sides, 1, 1, suitably connected and braced by cross rods 2, 2, and a foot rest 3; suitably attached to the top of the device is a cover piece 4, which protects the device from mechanical injury, dust and dirt, and which may also serve as a foot rest. Upon the inside surfaces of the upright sides 1, 1, are bosses 5, 5, Figs. 5 and 6, and upon said bosses 5, 5, is suitably swivelled as by screws, bolts, etc., a swinging member comprising horizontally projecting arms 6, 6, with their extremities 7, 7, joined by a connecting bar, for example a square rod 8 suitably attached by screws or otherwise; mounted upon said square rod 8 is a tube or other hollow rod 9 having a square hole shown in Fig. 2; the tube 9 is shorter than the rod 8, and is provided with end pieces or flanges 10, 10; between said flanges 10 and the ends 7 of the arms 6, and surrounding the square rod are springs 11, 11, which serve to keep the tube 9 centrally located upon the square rod 8; projecting inwardly from the sides 1, 1, of the device are lugs or locking bars 12, 12, provided with supporting ends 12a which serve to keep the movable tube 9 in a neutral, locked, or horizontally immovable position until said tube 9 and its accompanying elements are lifted from the horizontal position and the flanges 10, 10, are above and free from the lugs 12, 12, Fig. 4.

Upon said flanges 10 are mounted electric contacts 13, 13, which are arranged to make contact with contact pieces 14, 14, which latter are mounted upon the arms 6, 6, 5 said electric contacts 13, 14 functioning as a switch to be closed by a foot movement described hereafter. Upon the surface of the tube 9, are mounted projections knobs, or other protruding shapes 15, between which 10 are spaces 16, the knobs 15 serving to engage the toe of a shoe, 18, Fig. 6, when the foot is placed within the device and raised to lift the tube 9 free from engagement with the locking means 12, 12, as shown in Fig. 4, 15 and after which the tube 9 may be moved to the right or the left by a foot movement, Fig. 6, against the pressure of one of the springs 11, and thereby make contact between contact points 13 and 14, as shown 20 at the left hand end of Fig. 6, thereby closing an electric circuit, and electrically discharging the asphyxiating or irritating gases, or actuating any other type of electric alarm or signal. Upon removal of the foot, 25 the lifted tube 9 will fall back by gravity, or may be pressed back by a spring, not shown, into the normal horizontal position, Figs. 2, 3, and 5, whereupon the springs 11 will press the said tube 9 into a central or 30 neutral position and the flanges 10 will then be engaged or locked by the lugs 12, as shown in Fig. 5.

I claim:—

- 25 1. A foot control contact, comprising a rigid structure, swinging members, said swinging members having a horizontal connecting bar, locking means, a slideable element on said connecting bar, said locking means arranged to hold said element locked 100 against accidental movement when said element is in the neutral position, electric contacts, and said contacts arranged to be closed by a movement of said slideable element after said element has been unlocked.
- 40 2. A foot control contact, comprising a rigid structure, swinging members, said swinging members having a horizontal connecting bar, locking means, a slideable element on said connecting bar, springs to press said slideable element into a neutral position, 105 said locking means arranged to hold said slideable element locked against accidental movement when said element is in the neutral position, foot engaging surfaces on said 110 slideable element, electric contacts, and said contacts arranged to be closed by a movement of said slideable element after said element has been unlocked.
- 45 3. A foot control contact, comprising a rigid structure, swinging members, said swinging members having a horizontal connecting bar, locking means, a slideable element on said connecting bar, springs to press said slideable element into a neutral position, 115 said locking means arranged to hold 120

said slideable element locked against accidental movement when said element is in the neutral position, foot engaging surfaces on said slideable element, said slideable element adapted to be moved against the pressure of said springs after said element has been unlocked, electric contacts, and said contacts arranged to be closed by a movement of said slideable element after said slideable element has been unlocked.

In testimony whereof I hereby affix my signature.

FRANK J. BRIDGEMAN.
